Specification for Design.

Patented Mar. 7, 1922.

Application filed December 20, 1920. Serial No. 432,122. Term of patent 7 years.

To all whom it may concern:

Be it known that I, JOHN P. DRISH, a citizen of the United States, residing at Chicago, in the county of Cook and State of Illinois, have invented a new, original, and ornamental Design for Automobile Tire Treads, of which the following is a specification, reference being had to the accompanying drawings, forming part thereof.

The figure is a face view of the tread portion of a tire, showing my new design.

I claim:

The ornamental design for an automobile tire tread, as shown.

JOHN P. DRISH.
